UNITED STATES PATENT OFFICE

CLARENCE HILL SMITH, OF FALMOUTH, MASSACHUSETTS, ASSIGNOR TO
POWER DEVELOPMENT COMPANY, OF PORTLAND, MAINE, A CORPO-
RATION OF MAINE.

SUPERHEATER.

No. 831,998.

Specification of Letters Patent.

Patented Sept. 25, 1905.

Application filed January 29, 1906. Serial No. 298,398.

To all whom it may concern:

Be it known that I, CLARENCE HILL SMITH, of Falmouth, in the county of Barnstable and State of Massachusetts, have invented certain new and useful Improvements in Superheaters, of which the following is a full, clear, and exact description, reference being had to the accompanying drawings, forming part of this specification.

10 This invention has reference to improvements in superheaters for water or steam, and particularly to such superheaters designed for use in water-tube boilers.

One object of the invention is to so construct a superheater of this nature that access may be had to the superheater for repairing the same or for the removal or insertion of tubes.

Another object of the invention is to improve the construction of the superheater and the means whereby the same is included in the circulation system of the boiler.

Other objects of the invention will appear from the following description.

25 The invention consists in the peculiar construction of the superheater.

The invention also consists in the peculiar manner in which the superheater is connected with the boiler.

30 The invention still further consists in such other novel features of construction and combination of parts as shall hereinafter be more fully described, and pointed out in the claims.

Figure 1 represents a vertical sectional view of a water-tube boiler, illustrating the construction of the superheater and its connection with the water-circulating system thereof. Fig. 2 represents a plan view of the superheater, illustrating its relation to the 40 side wall of the boiler.

Similar numbers of reference designate corresponding parts throughout.

The superheater is herein illustrated in combination with a water-tube steam-boiler set in the usual manner, which setting has the front wall 5, the side wall 6, and the bridge-wall 7, between which bridge-wall and the front is located the furnace or fire-box 8. From the upper part of the bridge-wall extends the baffle-plate 9, having the forwardly-inclined deflector member 10, adapt-

ed to direct the products of combustion forward. The rear wall 11 has the outlet 12, preferably provided with the usual damper 13, the boiler being covered in by the top 14 of any well-known heat-resisting material. At the rear portion of the setting is located the inclined baffle 15, from the lower end of which extends the deflector 16.

The cross-drums 17 and 18 at the upper part of the boiler-casing are connected by the water-circulating tubes 19 and by the steam-tubes 20, the ends of which are secured in the respective drums. From the drum 18 depends a series of tubes 21, which are connected at their lower ends with the header 22, which in turn is connected by a series of tubes, as with the lower mud-drum 24. The header 22 is also preferably connected with the front upper drum 17 by the series of tubes 25, while the mud-drum 24 is preferably connected by the series of tubes 26 with the front header 27, which in turn is connected to the front upper drum 17 by a series of tubes, as 28.

The rear upper drum 18 has the water-inlet pipe 29, the steam-outlet pipe 30, and the superheater connecting-pipe 31, furnished with the valve 32. The outlet-pipe 30 has the valve 33, and from this pipe extends the 75 valved pipe 34, having the valved blow-off pipe 35 and the steam-delivery pipe 36, extending from the superheater. From the front upper drum 17 extends the superheater water-supply pipe 37, having the valve 38, 80 beyond which valve this pipe 37 communicates with the drain-pipe 39 and with one section of the superheater. As the pipes 31, 36, 37, and 39 and their valves are outside the side wall 6, as indicated in Fig. 2 of the 85 drawings, said valves are accessible for controlling the passage of water or steam through said pipes.

The superheater preferably comprises three pairs of sinuous vertical boxes in the 95 nature of headers, located in or supported by the wall 6 and extending from the outer side thereof. These boxes 40 41, 42 43, and 44 45 are preferably arranged in offset relation both horizontally and vertically, as shown in 100 Fig. 1 of the drawings, and in each pair of said boxes are secured the ends of a series of cir-

culating-tubes 46, 47, and 48, which extend transversely of the boiler, the ends of these tubes being preferably secured in staggered relation in said boxes, whereby space is economized without weakening the boxes and the tubes are subjected to the action of the products of combustion circulating therebetween, while the vertical and horizontal arrangement of the several series of tubes is designed to be acted upon by the heated gases passing horizontally or vertically. The box 40 is connected by the pipe 49 with the fitting of the water-supply pipe 37 and by the pipe 31 with the drum 18. Circulation is furnished from the box 40 through the tubes 46 to the box 41, thence by the pipe 50 to the box 42, through the tubes 47 to the box 43, through the pipe 51 to the box 44, and through the tubes 48 to the box 45, which communicates with the steam-delivery pipe 36. The valve 38 being open, water supplied to the boiler in any usual manner, as by means of the inlet 29, will fill the boiler-tubes and the drum 24, also partially filling the drums 17 and 18 and filling the superheater and its pipe 36 to a level with the water-level in said drums. The valve 33 is now preferably closed and the valve 32 is opened, as also the valve of the blow-off pipe 35, to open an exit for the wet steam generated in the superheater. The products of combustion pass upward from the fire-box, circulating around the tubes 25 and 26, and are then directed forward by the deflector member 10, after passing beyond which the gases circulate toward the tubes 19 and 20 and thence downward between the baffle 9 and the baffle 15 until they pass beneath the lower edge of the deflector 16. In this rearward and downward passage the gases circulate about the tubes of the superheater and raise the temperature of the same and of the water or steam circulating therein.

Under the action of the heated gases the water in the boiler-tubes 25 and 26 circulates toward the drum 17, and hence to the drum 18, through the tubes 19, the steam passing through the tubes 20. The water in the superheater circulates through the several series of boxes and their tubes, and the steam generated from said water finds an outlet through the pipe 36 to the blow-off pipe 35. When the steam passing from the blow-off pipe is found to be sufficiently dry, the valve of said pipe is closed, as is also the valve 33, while the valves of the pipes 34 and 31 are opened, thus allowing steam to pass from the drum 18 through the pipe 31 to the box 40 of the superheater and thence through the several boxes and systems of tubes thereof to the pipe 31 and through the pipe 34 to the main steam-pipe 30. When desired, any water in the superheater may be drawn off through the drain-pipe 39.

Reference to ordinary and well-known features of construction of the boiler and superheater have been omitted from the above description, as they do not form part of the present invention. It is understood that the usual machine-shop practice in boiler construction will be followed and that mechanical equivalents for the parts herein broadly described may be used without thereby limiting the present invention.

Having thus described my invention, I claim as new and desire to secure by Letters Patent—

1. A superheater for steam-boilers comprising a series of pairs of headers arranged in staggered relation, one of each of said pairs of headers being connected with one header of the next adjacent pair, and tubular connections between the headers of each pair.

2. The combination with a steam-boiler having upper front and rear drums, and water-circulating tubes connecting said drums, of a superheater comprising a series of tubes extending transversely of the boiler below said water-circulating tubes, headers in which the ends of said tubes are connected, a steam-pipe connecting the steam-space of the rear drum with one of said headers, and connections between the other of said headers and the steam-delivery main.

3. The combination with a steam-boiler having upper front and rear drums, and tubes connecting said drums, of a tubular superheater located approximately between said drums, connections respectively between the water-space of the front drum and said superheater, and between the steam-space of the rear drum and said superheater, and a connection between said superheater and the steam-delivery main.

4. The combination with a steam-boiler having upper front and rear drums, and tubes connecting the same, of a superheater located approximately between said drums and connected with the steam-delivery main, a connection between the steam-space of one of said drums and the lower portions of the superheater, and a water-supply pipe connecting with said superheater.

5. The combination with a steam-boiler having a drum designed to receive steam, of a superheater comprising a series of pairs of headers, each pair connected by transversely-extending tubes, and connections between each of said pairs of headers, a connection between one of said headers and the steam-space of said drum, a water-supply pipe connecting with one of said headers, and a steam-outlet pipe connecting one of said headers with the steam-delivery main, said outlet-pipe being furnished with a valved blow-off pipe.

6. The combination with a boiler having a

steam-space, of a superheater comprising a series of steam or water circulating elements arranged transversely of the boiler and offset both vertically and horizontally, said several 5 elements being connected in series, a connection between the lower of said elements and said steam-space, a water-supply pipe connected with the lower of said elements, and a

steam-delivery pipe connected in the upper of said elements.

In testimony whereof I affix my signature in presence of two witnesses.

CLARENCE HILL SMITH.
